UNITED STATES PATENT OFFICE.

RICHARD O'NEILL, JR., OF NEWARK, NEW JERSEY.

BUCKLE.

No. 895,391.

Specification of Letters Patent.

Patented Aug. 4, 1908.

Application filed January 21, 1908. Serial No. 411,889.

To all whom it may concern:

Be it known that I, RICHARD O'NEILL, Jr., a citizen of the United States, residing at Newark, in the county of Essex and State of New Jersey, have invented certain new and useful Improvements in Buckles; and I do hereby declare the following to be a full, clear, and exact description of the invention, such as will enable others skilled in the art to 10 which it appertains to make and use the same, reference being had to the accompanying drawings, and to figures of reference marked thereon, which form a part of this specification.

15 This invention relates to an improved belt clasp or buckle which can be used on waist belts or as a collar clasp, or any similar position where an encircling band is adjustably fastened end to end.

20 This device provides for a belt without perforations, such as are used when a buckle is employed, and the belt can be tightened or loosened without removing it from the person so that when occasion requires, an adjustment of the belt can take place without attracting unnecessary attention. The clasp in this case is of the kind that is normally held locked by the strain on the belt itself.

The invention is illustrated in the accompanying drawing, in which Figure 1 is a perspective view of a belt provided with my improved clasp or buckle. Fig. 2 is a section of the clasp, and Fig. 3 is a perspective view of the clasp showing the 35 back of it.

The illustration shows a belt having a body portion 10 of any of the usual materials employed, and on one end of the belt is a member 11 forming a hook, preferably, but it can 40 be made to engage in any of the other usual ways with the other member of the clasping device to be hereinafter described. The engaging member 11 has any suitable clasp 12 to secure it to the end of the body portion 10. 45 The free end 13 of the body portion 10 is the end that is used for the adjusting of the belt, and it passes through a clasp which consists of a plate 14 which can be suitably figured or ornamented, but which is preferably made 50 substantially U-shaped, thus acting to shield the free end of the swinging plate, to be described hereinafter, from accidental opening or swinging. A staple 15 extends across the back of the clasp and is the element that is 55 engaged by the hook 11. On the reverse side and at the open end of the substantially

U-shaped portion of the clasp is a bridge 16 which has a bottom 17, which bridge and staple 15 form a channel through which passes the free end 13 of the body portion of 60 the belt 10, and the clasp is free to slide on the body portion when it is not positively locked. The bottom portion 17 of the bridge 16 is preferably provided with one end, 18, slightly turned up to form a ridge, and this 65 engages one side of the belt 10.

Pivoted as at 20, in the ends of the bridge 16, is a swinging plate 19 which, with its right-angled portion 21, forms a clasping plate, and it has a free end 22 provided for its 70 manual manipulation. It will be evident therefore that when this clasping plate is in the position shown in Fig. 2, the clasp is locked on the belt so that there is no slipping. When the end 22 is swung out however, the 75 pressure is taken from the end 21 and the belt is free to slip through its channel in the clasp and to be adjusted thereon. This clasping plate is on the exterior of the clasp to provide a ready means for adjustment 80 when the belt is on the wearer, and the belt can be taken up and let out, which is a decided advantage, as it saves time and annoyance.

The construction of the buckle with the 85 clasping plate inside the frame, when in locking position, saves the free end of the swinging plate from accidental engagement with projections, and thus prevents accidental loosening of the belt. 90

Having thus described my invention, what I claim is:—

1. A clasp comprising a plate having an opening in its face and having a channel in the back thereof for the passage of the free 95 end of a belt, and a swinging clasp plate attached to the first mentioned plate having a portion for grasping the belt in its channel and having a free end for its manual manipulation, the free end of the swinging plate being within the said first mentioned plate when in its locked position, whereby it is shielded from accidental opening. 100

2. A clasp comprising a substantially U-shaped plate having a bridge on the back of 105 its open end, a clasping plate pivoted in the open end and having a free end for its manual manipulation and a right-angled portion for clamping a belt on the bridge, the free end of the clasping plate being normally within the 110 U-shaped plate, the clasping plate swinging to the front of the buckle, and means for de-

tachably securing the clasp to the other end of the belt.

3. A clasp comprising a substantially U-shaped plate having a bridge on the back of its open end, a clasping plate swinging in the ends of the bridge, the clasping plate having a free end to swing on the front of the clasp and within and out of the U-shaped plate and having a right-angled portion to clasp a belt 10 on the bridge, and a staple on the back of the

plate and guiding the free end of a belt between it and the plate.

In testimony, that I claim the foregoing, I have hereunto set my hand this 20th day of January 1908.

RICHARD O'NEILL, JR.
